HAROLD L. PETTIT, OF WATERTOWN, NEW YORK, ASSIGNOR OF ONE-HALF TO NELLIE M. PETTIT, OF WATERTOWN, NEW YORK.

SPRAYING-NOZZLE.

1,295,922.

Specification of Letters Patent.

Patented Mar. 4, 1919.

Application filed March 14, 1918. Serial No. 222,364.

To all whom it may concern:

Be it known that I, HAROLD L. PETTIT, a citizen of the United States, residing at Watertown, in the county of Jefferson and State of New York, have invented certain new and useful Improvements in Spraying-Nozzles, of which the following is a specification.

This invention relates to improvements in spraying nozzles, designed for use in connection with paper-making machines, for breaking-up or dissipating the foam which usually gathers on the surface of the liquid pulp as it flows from the flow-boxes to the Fourdrinier wires.

The object of the invention is to provide a novel, simple and effective spraying device of the class, which consists of a hollow casing adapted to be connected with a suitable source of water pressure, and a valve which co-operates with a spraying member for discharging the water from the open end of the casing in a fine funnel-shaped spray, which effectually destroys the foam before it reaches the said wire. And a further object is to provide adjustable means for holding the valve in place under different degrees of water pressure.

I attain these objects by the means set forth in the detailed description which follows, and as illustrated by the accompanying drawing, in which—

Figure 1 is a side view of part of the wet-end of a paper machine and a partial section of the flow-box; showing my improvement applied thereto.

Fig. 2 is an enlarged side elevation of the spraying nozzle.

Fig. 3 is a central longitudinal sectional view of the same.

Fig. 4 is a detail view of the valve and spraying member.

Fig. 5 is a front end view of the device.

In the drawing, 2 represents generally the wet-end of a paper machine, and 3 the flow-box which contains and delivers the liquid paper-stock or pulp 4 to the machine. The pulp 4 upon leaving the flow-box 3 flows over an apron or dam 5, and falls into a trough 6, which carries the pulp onto the Fourdrinier wire 7. The agitation of the pulp flowing over the apron 5 and falling into the trough 6 creates a considerable amount of foam, as 4' (Fig. 1), which, unless broken-up or destroyed interferes with the proper making of the paper. Hereto-

fore, various spraying devices have been employed for destroying the foam, but none of these devices have been entirely satisfactory, principally because the sprays have been too coarse or lacked proper distribution over the foam area, to effectually break up the fine bubbles comprising the foam. It is a particular object of the present invention to provide a spraying nozzle, which is capable of delivering a fine and powerful spray that destroys the foam before it reaches the Fourdrinier wire without injuriously diluting the pulp. The following is a detailed description of my improved spraying device:

9 represents a casing or body, having an enlarged cylindrical portion 10, which is bored out centrally, as at 11, for forming a relatively large valve and spraying chamber, the said bore extending somewhat reduced, as at 12, to the opposite end of the portion 10. 13 represents a lateral intake nipple for connection with a suitable water-supply pipe, as 14, which preferably extends across the front end of the flow-box 3, and to which, in practice, four or five of the spraying nozzles are usually applied. The nipple 13 conducts the water, preferably under considerable pressure, into the interior of the casing 9. The casing 9 has a reduced threaded extension 15, which is bored out longitudinally to receive and support a valve-stem 16. 17 represents a circular or disk-like valve formed or mounted on one end of the stem 16 which is disposed within the casing 9, the said valve being disposed in the outer end and having a diameter slightly less than the diameter of the bore 11, so as to allow the water contained in the chambers 11 and 12 and under pressure, to escape around the valve in a funnel-shaped spray, as indicated by the broken lines in Figs. 1 and 3. To produce the proper spraying effect the valve 17 should be flush with the end of the casing, as shown in Fig. 3. Within the chamber 11 and also formed or mounted upon the valve-stem 16, is a cylindrical spraying member 18, which is normally spaced from the valve 17 and 19 arranged at the intersection of the chambers 11 and 12. The spraying member 18 substantially fits and fills the bore of the chamber 11, and its circumferential surface is provided with a number of grooves 20 having a helical pitch, through which the

water passes from chamber 12 to chamber 11 and in so passing is given a whirling motion. As the water leaves the grooves 20, it is thrown forwardly centrifugally in 5 a number of fine streams or jets which strike the inner surface of the chamber 11 adjacent the periphery of the valve 17. The water is then forced outwardly through the thin annular space 17' which surrounds the 10 valve 17, and owing to the whirling motion and force of the water and the shape of the disk 17, the water on leaving the valve 17 is projected in a fine funnel-shaped spray, over a relatively broad area, as indicated. 15 The stem 16 passes through the reduced end 15 of the casing, also through a gland-nut 21 and a packing 22, and extends a considerable distance beyond these parts. The packing 22 is employed for preventing leakage 20 of the water through the reduced end 15 of the casing. The outer end of the stem 16 is provided with a knob or button 23, by which the stem may be manipulated for cleaning the valve and the chamber 11 25 (see dotted lines in Fig. 3). In order to properly hold the valve 17 and spraying member 18 in place, as shown in full lines in Fig. 3, while said parts are subjected to the relatively high water pressure, I provide 30 a spring 24, which surrounds the stem 16 just beyond the gland-nut 21, one end of the spring engaging the gland-nut, while the opposite end engages a common nut 25, which is adjustable on the threaded outer 35 end of the stem, as shown.

Having thus described my invention, what

I claim as new and desire to secure by Letters Patent, is—

1. A hollow body having a cylindrical bore normally open to the atmosphere at one end, and having a similar reduced concentric bore and a shoulder at the intersection of said bores, a valve stem passing through said body, a disk valve carried by one end of said stem and disposed within and held flush with the open end of the larger bore, and a cylindrical enlargement on said stem within said larger bore, said enlargement being resiliently held against said shoulder for holding said valve flush with the open end of the larger bore. 40

2. A spraying nozzle including a casing having in one end a normally open cylindrical valve chamber separated from a smaller concentric chamber by an annular shoulder, a valve-stem partially disposed in said casing, a cylindrical valve mounted on one end of said stem disposed concentrically within the open end of said chamber, said valve having a smaller diameter than 55 the mouth of said chamber, a spraying member carried by said stem spaced from said valve and having substantially the same diameter as said chamber, said member engaging the shoulder and having circumferential grooves for the passage of the water, a spring for holding said member against said shoulder and said valve flush with the end of said casing, and means for increasing and decreasing the tension of said spring. 60

In testimony whereof I affix my signature.

HAROLD L. PETTIT. 65
